UNITED STATES PATENT OFFICE.

JAMES KELLY, OF PROVIDENCE, RHODE ISLAND, ASSIGNOR OF ONE-HALF
TO JAMES D. MINTO, OF PROVIDENCE, RHODE ISLAND.

AIR COOLING AND HUMIDIFYING APPARATUS.

No. 847,185.

Specification of Letters Patent.

Patented March 12, 1907.

Application filed September 15, 1905. Serial No. 278,651.

To all whom it may concern:

Be it known that I, JAMES KELLY, a citizen of the United States, residing at the city and county of Providence, in the State of Rhode Island, have invented certain new and useful Improvements in Air Cooling and Humidifying Apparatus, of which the following is a specification.

This invention has relation to air cooling and humidifying apparatus, and has for its object the provision of a novel apparatus adapted to cool, purify, and moisten air and discharge the same into apartments, such as textile machinery rooms and other apartments where the air is liable to be dry and charged with particles of dust or fiber detrimental to health; and the invention consists in the novel construction, combination, and arrangement of parts hereinafter described and claimed.

The invention is illustrated in the accompanying drawing, in the several figures of which like reference-letters designate corresponding parts, and in which—

Figure 1 is a side elevation of the complete apparatus. Fig. 2 is a detail view, partly in section, taken on the line $x-x$ of Fig. 1. Fig. 3 is a vertical longitudinal sectional view of a separator forming a part of the apparatus shown in Fig. 1, said figure being taken on an enlarged scale. Fig. 4 is a vertical transverse sectional view of the separator shown in Fig. 2 and taken on the line $y-y$ of said Fig. 2; and Fig. 5 is a detail vertical sectional view, on an enlarged scale, of a distributor forming part of the apparatus shown in Fig. 1.

The present invention is an improvement upon the ventilating and air cooling mechanism shown and described in Letters Patent of the United States No. 787,454, issued to me April 18, 1905, and is designed generally to perform the same functions as the apparatus shown and described in said Letters Patent; but embodies novel features of construction and operation adapted to perform the desired functions in a more perfect manner than they are performed by the apparatus of the patent.

Referring first to Fig. 1 of the drawing, a designates a fan-blower of appropriate form, this fan-blower receiving motion from any

suitable source of power through a belt a' and being provided with an air-inlet pipe a^2 and air-outlet pipe a^3 , the latter being provided with a valve a^4 . A pipe b is connected to the pipe a^3 by a suitable coupling b' , and the said coupling, which is a T-coupling, is connected to a relief-valve b^2 . The pipe b extends vertically above the pipe a^3 and then descends vertically and turns horizontally and connects with a T-coupling b^3 , which receives a large vertical pipe e and a similar horizontal pipe e' , the pipe e' being connected by a coupling e^2 with a horizontal pipe e^3 and a vertical stand-pipe f , said vertical pipe being some what larger than the pipes e^2 and e^3 and extending above the coupling e^2 , as shown. The coupling e^2 receives a short section of pipe f' in its lower side, which section seats in a supporting-standard f^2 and receives a water-supply pipe g and a steam-supply pipe g' , that are provided with valves g^2 g^3 , by means of which the supply of water and steam flowing through said pipes g g' may be regulated. The pipe e is connected to a horizontal pipe e^4 , and the pipe e^3 is connected to a vertical pipe e^5 , the pipes e^4 e^5 entering a check-valve casing i , in which is arranged a check-valve i' , which carries on its face a number of projecting pins i^2 , that serve to break up the water passing therethrough into small particles, as will be hereinafter more fully described. A pipe j extends upwardly from the valve-casing i and connects at j' with the vertical pipe f , said vertical pipe being provided with a reducing coupling j^2 , from which leads a small pipe j^3 , that is connected to a larger horizontal pipe k , which is in turn connected to a T-coupling k' , having a reduced end k^2 , from which a short pipe k^3 leads to a separator o . A pipe k^4 depends from the coupling k' and carries on its lower end a drip-pipe l , said drip-pipe being provided with a valve l' . The pipe k^3 extends into the coupling k' and is provided with a depending end n , that extends down into the pipe k^4 , and the pipe k^4 is provided with a water-gage m , by means of which the level of the dripped water in the pipe k^4 may be seen.

The separator o is shown on an enlarged scale in Figs. 3 and 4 of the drawing, and

this separator comprises a rectangular casing having a removable side o' , within which casing are arranged a series of angularly-disposed corrugated blades p , each of which extends from one wall of the casing to near the other wall of the same, leaving a sinuous passage between the sides and around the ends of said blades. The separator o carries a depending extension o^2 , that is provided with a drip-pipe r and a water-gage s , the former being provided with a valve s' , and the separator is provided with a pipe t , which pipe has a depending branch t' , on the lower end of which is arranged a distributor q , said distributor comprising the stationary bell q' and a deflector q^2 , the latter being provided with a pin-valve q^3 , which is vertically movable and connected to a lever q^4 , pivoted at q^5 to a bracket q^6 , carried by the deflector q^2 . The pin-valve q^3 governs an orifice q^7 in the center of the bell q' , and by moving the lever q^4 the said orifice can be opened or closed at will. The pipe f is provided with a gage y , which serves to indicate the pressure of the air and water within said pipe and is also provided with a thermometer y' to indicate the temperature of the air and water within said pipe f and with a water-gage y^2 to show the height of the water in said pipe f , the normal height of water being indicated by the dotted line h h , which, as shown, is just above the horizontal pipe e^4 .

As an adjunct to the apparatus above described I provide a tank or air-reservoir v , which is connected to the pipe b by a vertical pipe w and which tank or reservoir is charged with compressed air through a pipe u from any suitable air-forcing apparatus, such as a power-driven air-pump. (Not shown.) The pipe w is provided with a valve w' , and the tank v is provided with a relief-valve x .

The apparatus constructed in the above-described manner is operated as follows: Water under pressure is admitted through the pipe g and rises into the pipe f to the level shown by dotted lines h h and also fills the pipes e e' e^3 e^5 e^4 . Then when the fan a is set in motion the air-pressure caused thereby through the pipe b produces a circulation of the water through the pipes e' , e^3 , e^5 , e^4 , and e and causes the water to be driven against the valve i' and is broken up by contact with the points i^2 of the valve and ascends through the pipe j in the form of bubbles and also forced upwardly in the form of bubbles through the relatively large pipes f and passes into the contracted pipes j^3 , k , and k^3 to the separator o . The check-valve v' prevents the reverse circulation of the water and insures its passing in one direction only through the pipes e^4 and e . This system of piping thus divides the water and insures a more rapid action thereon by the air-currents. The air, heavily charged with mois-

ture, passes up through the depending end n 65 of the pipe k^3 and thence into the separator o , where the solid particles of moisture are separated from the air by the corrugated blades p , the deposited water flowing off through the depending pipe o^2 and drip-pipe r and the moistened air passing to the distributor q through pipe t and its extension t' . When a warm vapor is desired, hot water is let into the pipe g' , which is provided with a valve g^3 , that connects with any suitable source of supply. The discharge of air through the distributor q is regulated by means of the pin-valve q^3 , and the air coming from the distributor between the bell q' and the deflector q^2 will be spread in all directions from the edges of the distributors. The air-reservoir or tank v is adapted to be used alternatively to the fan-blower a , and in the event of the air tank or reservoir v being used the valve w' is opened and the valve a^4 is closed, the apparatus otherwise operating in the same manner as when the fan-blower is used. The pin-valve q^3 not only regulates the proper discharge of air through the distributor q , but also permits of its pin-point keeping the orifice q^7 of the same free of sediment.

By my construction and arrangement of parts I form an apparatus that contains in itself all that is necessary to give off either a cool vapor or a warm vapor, as may be desired.

Having now fully described my invention, what I claim as new, and desire to secure by Letters Patent, is—

1. In an apparatus of the character described, the combination of an air-forcing device, a plurality of pipes connected thereto and arranged in rectangular form, a stand-pipe connected at its lower end to said pipes, a water-supply pipe connected to said stand-pipe, a connection from the upper end of said rectangularly-arranged pipes to the upper part of said stand-pipe, a separator connected to said stand-pipe, and a distributor connected to said separator.

2. The combination with an air-forcing device, and a plurality of pipes arranged in rectangular form, of a stand-pipe connected at its lower end to said rectangularly-arranged pipes and connected at its upper end to the upper portion of said rectangularly-arranged pipes, a check-valve casing arranged at the upper connection of said rectangularly-arranged pipes, with said stand-pipe, and a flap-valve arranged in said casing and provided with projections on its face.

3. In an apparatus of the character described, the combination of a supporting-standard, a stand-pipe supported thereby, a coupling near the lower end of said stand-pipe, a water-pipe and a steam-pipe respectively leading into the lower end of said stand-pipe, horizontal pipes connected to

said coupling, vertical pipes connected to said horizontal pipes, a horizontal pipe connected to said vertical pipes, an air-supply pipe leading into one of said vertical pipes at its juncture with one of said horizontal pipes, a check-valve casing arranged at the juncture of the other of said vertical pipes with the upper horizontal pipe, and a pipe leading

from said valve-casing to the upper end of said stand-pipe.

In testimony whereof I affix my signature in presence of two subscribing witnesses.

JAMES KELLY.
